UNITED STATES PATENT OFFICE.

AARON WOLF, OF NEW YORK, N. Y.

CORNER-POST FASTENING.

1,120,638.

Specification of Letters Patent.

Patented Dec. 8, 1914

Application filed June 14, 1913. Serial No. 773,578.

To all whom it may concern:

Be it known that I, AARON WOLF, a citizen of the United States, and resident of New York city, in the county of New York and State of New York, have invented certain new and useful improvements in Corner-Post Fastenings, of which the following is a specification.

This invention relates to certain improvements in corner post fastenings, for bedsteads, and more particularly to the general type shown in the prior Patent No. 1,048,256, issued December 24th, 1912, to myself and Antoni Governale, and in the prior co-pending application, Serial No. 703,004, filed June 11th, 1912, by us.

The main objects of my present invention are to provide an improved lug formation for more effectively holding the cross rail 20 to improve and simplify the connection between the side rail and the corner post and to provide an improved connection between the fastening member and the corner post to prevent wear or injury of the latter, to 25 conceal the opening in the former, and to remove the necessity for absolute accuracy in manufacture.

In my present construction I also provide an improved construction facilitating the 30 insertion of the retaining wedge and provide a simple and efficient means for connecting the foot and head members when the bedstead is on exhibition and the normal side rails removed.

My invention involves other features which together with the details of the features above referred to will be more particularly pointed out hereinafter and defined in the claims.

Reference is had to the accompanying drawings in which similar characters of reference indicate corresponding parts throughout the several views, and in which—

Figure 1 is a top plan view of a construction embodying one form of my invention, the corner post, base plate and wedge being shown in section; Fig. 2 is a perspective view of the tubular member of the corner post fastening; Fig. 3 is a perspective view 50 of the terminal portion of the side rail; Fig. 4 is a perspective view of the base plate; Fig. 5 is a perspective view of the wedge for use within the corner post; Fig. 6 is a perspective view of a substitute side rail used for exhibition purposes; and Fig. 7 is

a top plan view of portions of the head and foot of the bedstead connected by the substitute side rail shown in Fig. 6.

In the specific form shown the corner post fastening includes a tubular member 10 of somewhat the same general construction shown in the prior Patent 1,048,256 above referred to and adapted to be secured to a hollow metal post 11. The tubular member is formed from a sheet metal blank bent to bring opposite edges together and to form four sides including the top 12, the bottom 13 and the two vertical side walls 14 and 15. The top and bottom walls have extensions 16 adapted to enter transverse slots in the post 11 and each extension is provided with a perforation or aperture 17 for the admission of a wedge 18 movable lengthwise of the post within the latter. The wedge is preferably formed of a piece of sheet metal bent to substantially semi-cylindrical or V-shape and tapered toward one end. The metal is so drawn that at the smaller end there is an end wall 19 inclined in respect to the general direction of the length of the pin so that the pin terminates in an edge in the plane of the longitudinal side edges, which greatly facilitates the admission of the pin or wedge to the apertures 17 and facilitates the drawing of the tubular member 10 into proper and rigid engagement with the post. This pin by being formed in this manner is less expensive than the cast metal pin shown in the prior patent above referred to and as it is hollow the opposite side edges have resiliency permitting the proper engagement with the sides of the hole. This insures the fit of the pin or wedge without the absolute accuracy otherwise required.

One of the special features of my present invention involves an improved construction facilitating the rigid attachment of the cross brace of the head or foot frame of the bedstead. The meeting edges of the blank 100 may be at either the upper or lower corner of the member and either at the inner or at the outer side, but is preferably at the upper inner corner as shown particularly in Fig. 2. The top wall 12 and the side wall 15 meet at the upper inner corner of the member with the top wall projecting out over the side wall. The top wall is provided with apertures and the side wall has lugs 20 adapted to extend through these 110

2
apertures and to be riveted over to secure the edges permanently together. Extending downwardly from the upper edge of the side wall 15 is an L-shaped slot defining a portion of the side wall which may be bent outwardly at right angles to the plane of the side wall, and constitute a lug 21. The top wall has an extension 22 lying in its own plane and extending out from the lug 21, so that the upper edge of the latter acts as a support for the outer free end of the former and the parts 21 and 22 lie in planes at right angles to each other and their meeting edges are at right angles to the general direction of the length of the tubular member 10. These lugs or flanges are of such size and so positioned that a cross brace 23 may be rigidly secured to each of them by bolts, rivets or other suitable means. The cross brace is ordinarily in the form of an angle-iron and as the two flanges 21 and 22 are in planes at right angles to each other, the angle-iron may be rigidly secured to both flanges and thus prevented from tilting or swinging as might occur if only one flange were employed. Furthermore, the cross brace can not be displaced by the bending of either one of the two lugs or flanges.

In the specific construction illustrated in the prior Patent No. 1,048,256, the side rail is in the form of an angle iron abutting against the end of the tubular member and the side rail carries a tubular member adapted to extend into the tubular member carried by the corner post. In the specific form illustrated in the prior application, Serial No. 703,004, the angle iron extends into the tubular member of the corner post and rests upon a stationary support disposed therein. In my present and improved construction the side rail 24 which is in the form of an angle iron, extends into the tubular member of the corner post and carries its own support. This support is preferably in the form of a sheet metal plate having two portions 25 and 26 bent at right angles to each other. The portion 25 is longer than the portion 26 and is riveted to the inner surface of one of the flanges 27 of the angle iron side rail while the shorter portion 26, is disposed parallel with and opposite to the other flange 28 of the angle iron as is shown particularly in Fig. 3. The portion 25 is secured to the flange 27 by rivets 29 while the portion 26 and the flange 28 of the angle iron are provided with perforations 30 in alinement with each other. The top and bottom walls 12 and 13 of the tubular member 10 are also provided with perforations 31 so that when the angle iron and its supporting member are projected into the end of the tubular member, the openings may come into alinement with each other and a pin 32 may be inserted to lock the parts together. One special feature of my invention involves the utilizing of the rivets 29 as stops so that when the angle iron is forced endwise into the tubular member one of the rivets may abut against the end of a side wall of the tubular member and limit the inward movement of the angle iron. The perforations 30 and 31 are so placed that with the angle iron in its limiting position the perforations 30 will have their centers slightly beyond the centers of the perforations 31 but they will be substantially in alinement. The tapered pin 32 may be dropped into place but upon driving it home the angle iron will be forced backwardly a very slight distance from the position shown in dotted lines in Fig. 1 to the position shown in solid lines. Thus one of the rivets 29 serves as a stop to insure the substantial alinement of the openings but moves back upon the driving of the pin into position, so as to not interfere with the proper locking action of the latter. The two perforations 30 are of substantially the same size and the wall 26 of the supporting member is of such a length that its outer end terminates substantially flush with the end of the tubular member 10 when the parts are in proper position. Thus the angle iron may be inserted with the flange 28 as a top wall as shown in Figs. 1 and 3 or it may be turned over and have its ends reversed so that the flange 28 is at the bottom and may serve as a support for a series of bed slats in case it is desired to use such in place of the ordinary metal spring frame.

Although when the bedstead is set up I preferably employ a side wall formed of an angle iron and a supporting member as shown in Fig. 3, yet when the bed is on exhibition or being shipped, I provide a special form of connecting member as shown in Fig. 6. This connecting member involves a piece of channel iron 33, having its opposite flanges provided with perforations 34, the size of the channel being such that it will fit into the tubular member. The head and foot of the bed may be brought together as indicated in Fig. 7 with the channel 33 connecting them and holding them rigid in respect to each other. This form of channel iron is inexpensive to manufacture and is very effective in holding the parts in proper relative positions. The same pins 32 are used in securing this channel in position as are used in connection with the side rails so that the pins are always in use and the liability of losing said pins is thus very much reduced if not eliminated.

One of the most important features of my invention involves the plate 35 shown particularly in Fig. 4. This plate is substantially rectangular in form and is curved, bent or flat depending upon and conforming to the shape of the post. The plate has two slots 36 therein which are of such size and

so positioned as to receive the extension 16-16 of the tubular member and to lie in alignment with the slots in the post, which receive said extensions. This plate performs 5 several important functions. It is preferably of steel, whereas the post itself is often of softer brass or is brass coated or enameled. The vertical end of the side walls 14 and 15 of the tubular member come in direct contact 10 with the outer surface of the plate 35 and are prevented from marring the post or indenting or cutting into the latter due to relative movement of the parts in the movement of the bedstead. It distributes the pressure over such a large area of the post 15 that there is little if any marring of the latter and the corner post fastening may be removed from the post leaving the latter free from disfigurement. A further important 20 advantage of this plate is that it increases the range of the wedge 18, without exposing the openings 17. It is evident that the wedge 18 in being driven into place draws the extensions 16 into the post and 25 in doing so the free edges of the sides of the wedge approach the end of the opening 17 toward the body of the tubular member. If these openings 17 be made of such size 30 that they will be drawn into the slots in the sides of the post then there is the possibility that the wedge may come into engagement with the said end of the opening 17 and further downward movement of the wedge will have no effect in binding the parts. If the openings 35 17 are made of such size that there is no possibility of their being drawn into the slots in the post then they may be exposed and render the device unsightly as well as providing apertures through which vermin 40 may gain access to the interior of the post. The plate 35 permits the wall of the post to be comparatively thin, insures the concealing of the apertures 17 and avoids the possibility of the wedges binding against the 45 ends of the apertures toward the body of the tubular member. As indicated in Fig. 1 of the drawings the edges of the wedge are still a considerable distance from the end of the apertures 17, but at the same time 50 said apertures come within the slots 36 of the plate 35 and are concealed and protected. It is of course evident that I may employ this plate 35 as well as the wedge 18 and the 55 connecting channel 33 in the specific construction of tubular member illustrated in the prior Patent No. 1,048,256. It is also evident that I may employ all of the features above described and hereinafter claimed, in one device or that certain of the 60 features may be omitted without materially detracting from the efficiency of the others.

Most of the features constituting the subject matter of the present application were disclosed in my prior application 770,095 filed May 27th, 1913, and from which they

have been divided out. Various changes and rearrangements of the parts may be made without departing from the spirit of my invention and within the scope of the appended claims.

Having thus described my invention, what I claim as new and desire to protect by Letters-Patent, is:

1. A corner post fastening including a tubular member formed from a sheet metal blank with its opposite edges secured together, said member having a portion of one the top wall projecting outwardly laterally in the horizontal plane of said top wall and beyond the adjacent side wall to 75 form an attaching lug for a cross brace.

2. A corner post fastening including a member formed from a sheet metal blank presenting a top wall and a side wall rigid in respect to each other, said member having an extension in the plane of one wall of said member and extending outwardly beyond the meeting edges of the blank to form an attaching lug for a cross rail, and the adjacent wall of said member having a 85 portion bent outwardly to form a lug lying in a plane at right angles to the plane of said first mentioned lug.

3. A corner post fastening including a member formed of a blank of sheet metal 95 and presenting a top wall and a side wall, the top wall having a portion extending outward laterally beyond the side wall to form an attaching lug for a cross rail and the side wall having an opening therethrough 100 and a portion bent outwardly from the edge of said opening to form a second lug, lying in a plane at right angles to the plane of the first mentioned lug.

4. A corner post fastening including a 105 tubular member adapted to be secured in a substantially horizontal position to a corner post, an angle iron side rail having a supporting member secured thereto by rivets, said angle iron and said supporting 110 member being adapted to project endwise into said tubular member and said rivets serving to limit the inward movement thereof.

5. A corner post fastening including a 115 tubular member, a side rail member adapted to telescope therewith, said members having openings which may be brought into alignment upon said telescoping movement of said members, a stop for preventing said 120 telescoping member beyond a position with said openings substantially in alignment and a pin adapted to enter said aligned openings to secure said members together, said side rail member being moved slightly rearwardly from said limiting position upon insertion of said pin.

6. A corner post fastening including a tubular member, a side rail in the form of an angle iron and a supporting member in- 125

- cluding two portions at an angle to each other and of different lengths, the longer portion being secured to the inner surface of one side flange of said angle iron, the 5 shorter portion being opposite to and parallel with the other flange of said angle iron and said angle iron and said member being adapted to be projected endwise into said tubular member.
- 10 7. A corner post fastening including a tubular member, a side rail in the form of an angle iron and a supporting member including two portions at an angle to each other and of different lengths, the longer 15 portion being secured to one side flange of said angle iron, the shorter portion being opposed to and parallel with the other flange of said angle iron and said angle iron and said member being adapted to be projected endwise into said tubular member, the means for securing the longer portion of said second mentioned member to said angle iron serving to limit said inward 20 movement.
- 25 8. A corner post fastening including a tubular member having perforated extensions at one end and upon opposite sides, a corner post having slots adapted to receive said extensions and a wedge within said 30 post and disposed within said perforations, said wedge being of sheet metal and substantially U-shaped in cross section to permit resilient movement of the side edges toward and from each other and having an 35 inclined end wall terminating in an edge in the plane of the longitudinal side edges.
9. In combination, a hollow corner post having a transverse slot, a plate in engagement with the outer surface of said post and 40 having a slot registering with the first-mentioned slot, a side rail fastening member having vertical bearing portions adapted to engage with the outer surface of said plate and having an extension adapted to 45 project through said aligned slots into the interior of the post and having an aperture, the outer end of which terminates within said slot, and a wedge member with-

in said post and extending through said aperture.

10. In combination, a hollow corner post having a transverse slot through the wall thereof, a plate in engagement with the outer surface of said post and having an opening in alignment with said slot, a side 55 rail fastening member having an extension projecting through said opening and slot into the interior of said post and having a vertical bearing surface engaging with the outer surface of said plate and means within 60 said post for drawing said extension into the latter.

11. A corner post fastening including a member formed from a sheet metal blank and including outer and inner substantially 65 vertical and substantially parallel spaced side walls, a wall connecting said side walls and integral with both, and a top wall integral with the outer side wall and extending across the space between said walls and 70 engaging with the upper edge of the inner side wall and having a portion projecting in its own plane beyond said inner side wall to form an attaching lug for a cross brace.

12. A corner post fastening including a 75 member formed from a sheet metal blank and including outer and inner substantially vertical and substantially parallel spaced side walls, and a top wall integral with the outer side wall and extending across the 80 space between said walls and engaging with the upper edge of the inner side wall and having a portion projecting in its own plane beyond said inner side wall to form an attaching lug for a cross brace, and said inner 85 side wall having a portion bent outwardly to form a lug lying in a plane at right angles to the plane of said extension and also adapted to be secured to said cross rail.

Signed at New York city in the county of 90 New York and State of New York this 12th day of June, A. D. 1913.

AARON WOLF.
